UNITED STATES PATENT OFFICE.

GEORGE F. LOUGHREN, OF BOSTON, MASSACHUSETTS, ASSIGNOR OF ONE-HALF TO
FREDERICK C. LANGENBERG, OF CAMBRIDGE, MASSACHUSETTS.

DEVICE FOR HANDLING FOUNDRY FLASKS.

Application filed November 1, 1922. Serial No. 598,306.

To all whom it may concern:

Be it known that I, GEORGE F. LOUGHREN, a citizen of the United States, residing at Boston, county of Suffolk, State of Massachusetts, have invented a certain new and useful Improvement in Devices for Handling Foundry Flasks, of which the following is a specification, reference being had therein to the accompanying drawings.

10 This invention relates to apparatus for handling foundry flasks in connection with the operation of molding. In accordance with the usual foundry practice, after the pattern has been put in place and the sand rammed about it in the drag, or bottom section of the flask, it is necessary to turn this flask section bottom side up in order to permit the pattern to be drawn. This involves closing the flask with a temporary 15 cover held in place by clamps and wedges, and then inverting the flask. The turning of the flask has heretofore been done by hand and necessitates the lifting of a considerable weight, the flask with the wet sand 20 and pattern frequently weighing 175 pounds or more, thus imposing heavy labor upon the molder and his assistant, so that two men are usually unable to prepare more than about twenty flasks a day.

25

30

This invention has for its object to devise improved mechanical means whereby the temporary cover may be quickly secured in place and the flask lifted and turned with the expenditure of a minimum amount of muscular effort.

The more particular objects of the invention, together with means whereby the same may be carried into effect, will best be understood from the following description of one 40 form or embodiment thereof illustrated in the accompanying drawings. The particular construction described and shown has, however, been chosen for illustrative purposes merely, and, believing myself to be the first to produce a combined grapple and hoist for foundry flasks which will permit the flask to be readily lifted from the floor or usual bench and inverted thereon, I desire to claim the same broadly, and wish to 45 have it understood that the invention, as defined by the claims hereunto appended, may be embodied in a variety of forms without departure from its spirit and scope.

In said drawings:

55 Fig. 1 is a side elevation of the apparatus,

illustrating its use in connection with a flask secured in place in the clamps.

Fig. 2 is a similar elevation, partly broken away, and on an enlarged scale, of the grapple shown in Fig. 1, one of the clamps 60 being shown in section taken substantially on the line 2—2 of Fig. 3.

Fig. 3 is an end view of the grapple, looking from the right in Fig. 2.

Fig. 4 is a detail in side elevation, looking 65 in the direction of the arrow in Fig. 2, of one of the clamps.

Fig. 5 is a detail plan view of a portion of the supporting bar.

The device as a whole, as herein shown, 70 comprises a bar 10 supporting a pair of arms 11 which carry at their lower ends clamps for grasping the opposite ends of a flask 12, said supporting bar being carried by a suitable hoist 13 by which the grapple may be 75 raised or lowered, and said clamps being so mounted in the arms 11, as hereinafter more fully described, as to permit the flask 12 to be inverted when the same has been lifted by the hoist 13.

As shown, the supporting bar 10 is T-shaped in cross section, the vertical flange thereof being turned upwardly and being connected by links 14 with a ring 15 adapted to be engaged by the hook 16 on the hoist 85 13, which hoist may be of any suitable form, but which is preferably provided with an operating chain or other member 17 extended to a convenient point adjacent the foundry floor. The horizontal flange of the 90 supporting bar 10 carries brackets 18, having portions overlying said flange, as shown in Figure 3, and secured thereto in adjusted position by means of pins 19 passing through said brackets and through any one 95 of a series of holes 20 (Figure 5) in said flange.

The arms 11 are pivoted respectively to the brackets 18, as by bolts 21, and are connected below their pivots by a yielding telescopic strut comprising a tubular member 22 pivoted at 25 to one of said arms, a rod 23 pivoted at 26 to the other of said arms and received in said tube, and a spring 24 (Figure 2) interposed between the end of 100 said rod and the bottom of said tube, said spring tending to separate said arms.

Each of the arms 11 has formed at, or has 105 secured to, its lower end an eye 27 in which is journalled a hollow trunnion 28 on a head 110

29, which head is thereby pivotally or rotatably mounted in said arm. Each of the heads 29 is formed with oppositely extending lateral projections 30 to which are secured, as by means of plates 31 and bolts 32, a pair of fixed clamping members 33 formed with jaws 34. The projections 30 and plates 31 of each of the heads 29 also form between them guideways for a pair of movable 10 clamping members 35 having jaws 36 opposing the jaws 34 of the fixed clamping members 33. The movable clamping members 35 of each clamp are normally moved away from the fixed clamping members thereof, 15 and into a position to open the clamp, by means of springs 38 surrounding said members and interposed between the head 29 and pins 39 extending through said clamping members. Also the movable clamping 20 members 35 of each clamp are connected on the opposite side of the head 29 from the jaws 36 thereof by a preferably integral bar portion 37 which is engaged and operated by a cam 40 (Figs. 2 and 4) having a 25 stem 41 extending axially through the hollow trunnion 28 and provided at the outer side of the corresponding arm 11 with a vice handle 42, whereby said cam may be operated to move the jaws 36 toward the 30 jaws 34 and close the clamp against the tension of the springs 38. The cams 40 are preferably so designed as to maintain themselves in adjusted position, so that the clamping members are practically locked in 35 clamping position.

In operation, after the pattern has been put in place in the flask 12 and the sand has been properly rammed, a cover 43 is placed upon said flask, the arms 11 of the grapple 40 drawn together against the tension of the spring 24, and the handles 42 operated to cause the cams 40 to close the clamps against the opposite sides or ends of the flask and cover, thereby not only grasping said flask 45 but holding said cover in place without the use of the devices usually employed for this purpose. The hoist 13 is then operated to lift the flask to a sufficient height above the floor or bench to permit the said flask to be turned, and said flask then inverted into the 50 position shown in Figure 1, the trunnions 28 in the eyes 27 permitting the clamps to turn with the flask. The handles 42 are then operated to turn the cams 40 in the opposite direction, permitting the springs 48 to open the clamps, whereupon the spring 24 will swing the arms 11 outwardly, thereby disengaging the clamps from the flask.

It will be seen that the turning or inverting of the flask is permitted by the pivotal mounting of the clamps in the arms 11, and, in order to permit said clamps to turn freely, it is desirable that the trunnions of the two clamps be disposed substantially co-axially. 60 To this end the brackets 10 are so adjusted,

in accordance with the size of the flask, upon the bar 10 as to cause the arms 11 to assume a substantially parallel position when the clamps are closed upon the flask.

It has been found in practice that by the 70 use of the combined grapple and hoist above described, two men can readily handle from 80 to 100 flasks a day with less effort than they are able to prepare twenty a day by the methods heretofore in use. 75

What I claim is:

1. A device of the character described comprising a bar, means for raising and lowering said bar, a pair of arms pivoted to said bar and adjustable longitudinally 80 thereof, and means carried by said arms respectively for grasping a foundry flask and permitting the same to be turned.

2. A device of the character described comprising a bar, means for raising and lowering said bar, a pair of brackets carried by said bar and adjustable longitudinally 85 thereof, arms pivoted to said brackets respectively, and means carried by said arms respectively for grasping a foundry flask 90 and permitting the same to be turned.

3. A combined grapple and hoist for foundry flasks having a pair of arms and clamps pivotally carried by said arms respectively, said clamps each comprising a 95 pair of relatively movable jaws.

4. A device of the character described comprising a bar, means for raising and lowering said bar, a pair of arms pivoted to said bar, and clamps pivotally carried by said arms respectively, said clamps each comprising a pair of relatively movable jaws. 100

5. A combined grapple and hoist for foundry flasks having a pair of pivoted 105 arms, clamps pivotally carried by said arms respectively, said clamps being adapted respectively to grasp the opposite sides of a flask, means for closing said clamps, and springs for opening the same. 110

6. A combined grapple and hoist for foundry flasks having a pair of clamps mounted to turn on substantially co-axial pivots, said clamps each comprising a pair 115 of relatively movable jaws.

7. A device of the character described comprising a support having a pair of arms, a hoist for said support, heads having trunnions journaled in said arms, respectively, clamps carried by said heads, and means 120 for operating said clamps.

8. A device of the character described comprising a support having a pair of arms, a hoist for said support and heads having hollow trunnions journaled in said arms respectively, each of said heads having a fixed clamping member, a clamping member movable thereon toward and from said fixed clamping member, and a cam for operating 125 said movable clamping member, said cam 130

having an operating stem extending through said hollow trunnion.

9. A device of the character described comprising a bar, a hoist for raising and lowering said bar, arms pivoted to said bar, heads pivoted to said arms respectively, a pair of clamping members carried by each of said heads, and an operating device for the clamping members of each pair.

10. A device of the character described

comprising a bar, means for raising and lowering said bar, a pair of brackets carried by said bar and adjustable longitudinally thereof, arms pivoted to said brackets respectively, heads pivoted to said arms ¹⁵ respectively, and clamping members carried by each of said heads.

In testimony whereof I affix my signature.

GEORGE F. LOUGHREN.
